UNITED STATES PATENT OFFICE.

ALLEN G. CLAMPITT, OF TWO RIVERS, WISCONSIN, ASSIGNOR TO THE HAMILTON MANUFACTURING COMPANY, OF TWO RIVERS, WISCONSIN, A CORPORATION OF WISCONSIN.

DESIGN FOR A TABLE.

45,410.

Specification for Design.

Patented Mar. 17, 1914.

Application filed January 12, 1914. Serial No. 811,766. Term of patent 7 years.

To all whom it may concern:

Be it known that I, ALLEN G. CLAMPITT, a citizen of the United States, residing at Two Rivers, in the county of Manitowoc and State of Wisconsin, have invented a new, original, and ornamental Design for Tables, of which the following is a specification, reference being had to the accompanying drawing, forming part thereof.

Figure 1 is a perspective view of a table,

showing my new design; Fig. 2 is a plan view; and Fig. 3 is a side elevation.

I claim:

The ornamental design for a table, as shown.

ALLEN G. CLAMPITT.

Witnesses:

BLANCHE CLAMPITT,
H. C. GOWRAN.
